UNITED STATES PATENT OFFICE.

ELLSWORTH S. BRYANT, ALEXANDER WILLIAM FINLAYSON, AND GEORGE R. COULS, OF DETROIT, MICHIGAN.

GAS-MAKING APPARATUS.

SPECIFICATION forming part of Letters Patent No. 340,282, dated April 20, 1886.

Application filed October 15, 1885. Serial No. 179,947. (No model.)

To all whom it may concern:

Be it known that we, ELLSWORTH S. BRYANT, ALEXANDER WILLIAM FINLAYSON, and GEORGE R. COULS, of Detroit, in the county 5 of Wayne and State of Michigan, have invented new and useful Improvements in Gas-Making Apparatus; and we do hereby declare that the following is a full, clear, and exact description thereof, reference being had to the accompanying drawings, which form a part 10 of this specification.

This invention relates to certain new and useful improvements in devices for manufacturing illuminating-gas, adapted to be used 15 in each household for the manufacture of such gas for home consumption.

The invention is designed to furnish ready and economical means for the manufacture of 20 gas by destructive distillation, by the use of which the evils arising from condensation in the pipe-service are reduced to the minimum.

The invention consists in the peculiar construction of the parts and their various combinations and operations, as more fully hereinafter described.

Figure 1 is a sectional elevation showing our invention as in operation. Fig. 2 is a perspective section showing one end of our improved retort. Fig. 3 is a sectional plan 30 showing the retort in place in the fire-box or combustion-chamber of a cooking-stove or range.

In the accompanying drawings, A represents a suitable vessel for holding water for 35 the purpose of washing the gas. This vessel is surmounted by a dome, B, which may be cast integral with the vessel, or secured thereto in any of the known ways of making pipe-joints. One or more perforations, a, in this 40 dome B allow the escape of the gas into the chamber C, which is fitted with a series of cross-supports, D, which are designed to contain or hold slaked lime or other of the known purifying materials for gas; and this chamber 45 is surmounted also by a dome or cap, E, in the top of which there are one or more apertures, b, to allow the gas to escape into the gas-holder F, which rises and falls in the water seal G. The vessel A, with its cap or dome 50 B, the chamber C, with its cap or dome E, and the walls of the water seal G may be cast in-

tegral or in separate parts properly secured together by gas-tight joints, as shown at H.

I is the retort, made in the usual way, closed at one end, while the front is provided with 55 an outwardly-projecting flange, c, having ears d cast integral thereon, by means of which the cover K is hinged to the front of such retort. This flange c has also formed upon it loop-flanges e, which hold the bar L in position to lock the cover in place; and a set-screw, M, passing through the center of such bar, with its ends engaging in the loop-ears e, affords the means for tightening the cover 60 against the end of the retort. To remove the 65 cover, the screw is turned backward and the locking-bar L disengaged from one of the loop-ears, when the door may be opened for recharging the retort. This retort may be of any desired shape, although shown in the 70 drawings to be cylindrical or round to fit within the combustion-chamber of an ordinary cooking-stove, N, and be inserted therein, if desired, through the fuel-door in one end thereof. A pipe, O, conducts the gas from 75 the retort into the lower part of the water-chamber A, whereby the gas, in passing up through the water, is washed and discharged into the chamber G, where it passes through the purifying mass upon the shelves and thence to 80 the gas-holder, whence it is taken out by the usual service-pipes to the burners.

P is a branch pipe, connecting with the pipe O at any convenient point, so that the open end of said pipe P may be let into the stove 85 pipe or flue Q, and at the point of intersection of this branch pipe P with the pipe O a two-way valve is inserted, so that if more gas is made than it is desired to discharge into the holder F the flow into such holder may be cut 90 off by turning the two-way cock and allowing the extra or superfluous gas to be discharged into such flue.

It will readily be seen that the retort being 95 filled with wood or coal, the ordinary fire of the cook-stove required for culinary and other purposes of the household will furnish the requisite heat for the destructive distillation of the contents of the retort. All the objections to making gas for household consumption in this way are removed by the apparatus attached thereto for washing and purify- 100

ing the gas. The same result might be obtained by the use of a kettle suitably connected with the gas-holder and its attachments, such kettle occupying one of the boiler-holes 5 above the fire-chamber and filled with the material from which the gas is to be destructively distilled and the cover suitably luted upon the top of such kettle.

Pipes *h* and *i* afford means for filling and 10 discharging the chamber A, when necessary.

We are aware that it is not new to pass the 15 gas generated in a retort through a washing-chamber and thence through a purifying-chamber, and therefore do not claim such, broadly.

Our invention lies in the peculiar construction, arrangement, and adaptation of parts, as specified in the appended claims.

What we claim as our invention is—

20 1. The combination, with a retort, of a gas-washing chamber connected therewith, a purifying-chamber formed integral with said washing-chamber and provided with a dome having a water seal, and a gas-holder above 25 said dome working in said water seal, substantially as described.

2. The combination, with a retort, of a gas-washing chamber connected therewith and

provided with a dome, a purifying-chamber arranged above the washing-chamber and 30 having communication therewith through perforations in said dome, a dome to the purifying-chamber having perforations, and a gas-holder above said dome, substantially as described.

35

3. The combination, with a retort, of a gas-washing chamber connected therewith and provided with a perforated dome, a purifying-chamber arranged above the washing-chamber and provided with racks D and a 40 perforated dome, a water seal on said dome, and a gas-holder working in said water seal, as set forth.

4. The chambers A D, formed integral and separated by a perforated dome, combined 45 with the detachable perforated dome E, having formed integral therewith the water seal G, substantially as and for the purposes specified.
